POCKET BOOK

Leo Kohn, New York, N. Y., assignor to Morris Moskowitz Corporation, New York, N. Y., a corporation of New York

Application August 23, 1950, Serial No. 11,887

Term of patent 3½ years

(Cl. D87—3)

To all whom it may concern:

Be it known that I, Leo Kohn, a citizen of the United States, residing at 60 Thayer Street, city of New York, in the State of New York, have invented a new, original, and ornamental Design for Pocketbook, of which the following is a specification, reference being had to the accompanying drawing, forming part thereof.

Fig. 1 is a front perspective view of a pocketbook embodying my new design, the back thereof being essentially the same in appearance as the front; and

Fig. 2 is a front perspective view illustrating the pocketbook in an open position.

I claim:

The ornamental design for a pocketbook, as shown and described.

LEO KOHN.
